UNITED STATES PATENT OFFICE

FRED WEINDEL, JR., OF ALLENTOWN, PENNSYLVANIA, ASSIGNOR TO THE E. INGRAHAM COMPANY, OF BRISTOL, CONNECTICUT, A CORPORATION

DESIGN FOR A CLOCK DIAL OR SIMILAR ARTICLE

Application filed August 13, 1931. Serial No. 40,839. Term of patent 7 years.

To all whom it may concern:

Be it known that I, FRED WEINDEL, Jr., a citizen of the United States, residing at Allentown, in the county of Lehigh and State of Pennsylvania, have invented a new, original, and ornamental Design for a Clock Dial or Similar Article, of which the following is a specification, reference being had to the accompanying drawings, forming part thereof.

Fig. 1 is a face view of a clock dial or similar article showing my new design; and

Fig. 2 is a sectional view on the line 2—2 of Fig. 1.

I claim:

The ornamental design for a clock dial or similar article as shown.
